UNITED STATES PATENT OFFICE.

DAVID J. SELL AND WILLIAM E. SELL, OF STURGIS, MICHIGAN.

NECK-YOKE CENTER.

SPECIFICATION forming part of Letters Patent No. 375,655, dated December 27, 1887.

Application filed May 9, 1887. Serial No. 237,646. (No model.)

To all whom it may concern:

Be it known that we, DAVID J. SELL and WILLIAM E. SELL, citizens of the United States, residing at Sturgis, in the county of St. Joseph and State of Michigan, have invented 5 a new and useful Neck-Yoke Center, of which the following is a specification.

Our invention relates to improvements in neck-yoke centers wherein a metal plate encircles 10 the neck-yoke and supports the carriage-tongue.

The object of our improvements is to form the neck-yoke center of a single metal plate encircling the neck-yoke and supporting the 15 carriage-tongue, thereby imparting strength and durability not heretofore attained. We effect this object by the mechanism illustrated in the accompanying drawings.

Figure 1 is a horizontal section of the neck-yoke center. Fig. 2 is a vertical section of the neck-yoke center, drawn through the dotted line on Fig. 1.

Similar letters refer to similar parts in both views.

25 A A is a continuous metal plate forming the neck-yoke center. One portion, being bent in a circular form, is lined with leather, a a a, encircles the neck-yoke, and revolves freely thereon, and has a rectangular flange, B, at the 30 end to receive nut-bolts c c'. The other portion of the plate forms a ring with the inner edge beveled, d d, and supports the carriage-tongue C. It is composed of two annular pieces of leather or its equivalent, with the external

edges beveled, which when joined form a ring 35 with a groove, D D, adapted to and bearing on the interior edge of the carriage-tongue supporter d d, and secured in position by being stitched to the leather covers F F, thus forming a substantial bearing for the carriage-tongue. 40 e is a metallic strip.

c c are nut-bolts passing through the flange B, the plate A A, the leather covers F F, and metal strip e, and securing the center around the neck-yoke. 45

We are aware that previous to our invention neck-yoke centers have been made of metal plates and leather. We therefore do not claim such a combination, broadly; but

What we do claim as our invention, and desire to secure by Letters Patent, is—

1. In a neck-yoke center, the combination of a single continuous metal plate encircling the neck-yoke and supporting the carriage-tongue by a ring beveled, substantially as described. 55

2. The combination, in a neck-yoke center, of a single continuous metal plate encircling the neck-yoke and supporting the carriage-tongue by a beveled ring covered with leather c c and containing a grooved ring, of leather or its equivalent, secured in position, substantially as shown, and for the purposes described.

D. J. SELL.
